COMBINED ASH TRAY AND RECEPTACLE FOR SMOKING MATERIALS

Frank J. Schroeder, Rochester, N. Y.

Application January 13, 1953, Serial No. 23,121

Term of patent 7 years

(Cl. D85—2)

To all whom it may concern:

Be it known that I, Frank J. Schroeder, a citizen of the United States of America, residing at Rochester, in the county of Monroe and State of New York, have invented a new, original, and ornamental Design for a Combined Ash Tray and Receptacle for Smoking Materials, of which the following is a specification, reference being had to the accompanying drawings, forming part thereof, in which:

Figure 1 is a top plan view of the combined ash tray and receptacle for smoking materials, showing my new design;

Figure 2 is a front elevational view thereof;

Figure 3 is an end elevational view thereof; and Figure 4 is a sectional view thereof taken along the line 4—4 of Figure 1.

The two circular configurations adjacent the

upper margin in Figure 1 are shaded to represent inclined circular cavities.

I claim:

The ornamental design for a combined ash tray and receptacle for smoking materials, substantially as shown.

FRANK J. SCHROEDER.
